Primary Examiner — Philip S Hyder*Assistant Examiner* — Roselynne Cody(74) *Attorney, Agent, or Firm* — Foley & Lardner LLP**CLAIM**

We claim the ornamental design for a hatchet, as shown and described.

DESCRIPTION

FIG. 1 is a front top perspective view of the claimed design; FIG. 2 is a left side view of the claimed design of FIG. 1; FIG. 3 is a right side view of the claimed design of FIG. 1; FIG. 4 is a front view of the claimed design of FIG. 1; FIG. 5 is a rear view of the claimed design of FIG. 1; FIG. 6 is a top view of the claimed design of FIG. 1; FIG. 7 is a bottom view of the claimed design of FIG. 1; and, FIG. 8 is a rear top perspective view of the claimed design of FIG. 1.

Areas of the drawings shown in broken lines are directed to features of the hatchet that form no part of the claim.
